FIG. 19.

BY

UNITED STATES PATENT OFFICE

ALFRED GIULIANI, OF NEW YORK, N. Y., ASSIGNEE TO DRY-WALL MFG. & CONSTRUCTION CO. INC., OF NEW YORK, N. Y., A CORPORATION OF NEW YORK

WALL CONSTRUCTION

Application filed November 7, 1929. Serial No. 405,826.

My invention relates to building wall construction intended for use on walls of buildings, or partitions between rooms of such buildings.

5 The object of the invention is to provide an improved construction of wall structure which comprises building up a wall or partition of blocks or slabs of concrete, cement, terra cotta or similar material, the blocks ¹⁰ 10 bracing beams placed at regular intervals along the line upon which the wall or partition is to be constructed, and being secured together and to said beams by means of tie rods.

15 A further object of the invention is to provide a construction which will eliminate the necessity of plastering, stuccoing, or otherwise finishing a wall or partition, thus reducing the price of building construction, particularly by the factor of labor and time saved.

20 A still further object of the invention is to provide a durable construction of wall structure and to provide an easy method of replacing portions of the wall which have become ²⁵ deteriorated.

The invention consists in the building up of a wall or partition, of blocks or bricks of particular shape and structure, placed between beams uniformly placed along the line ³⁰ 30 upon which the wall or partition is to be constructed, the blocks being built up to embrace said beams and being connected thereto by means of suitable bolts passing through said blocks and said beams. The faces of the ³⁵ 35 building blocks when superimposed upon each other according to the method herein-after described to the full height of the wall will thus form a smooth continuous surface.

40 In the accompanying drawings which illustrate various modifications of my invention,

Fig. 1 illustrates in perspective, one form of block to be used in my improved wall construction, the block being made of concrete or other similar composition, the face of which has a substantial thickness and is backed by flanges at its end portions.

45 Fig. 2 shows the same block in perspective but viewed from the rear.

50 Fig. 3 illustrates a block to be used in

accordance with my invention as a corner block.

Fig. 4 illustrates in partly sectional detail a portion of my improved construction with a number of the blocks matched to form my ⁵⁵ improved wall construction.

Fig. 5 shows a preferred form of block; Fig. 6 a rear view of the same; Fig. 7 a preferred form of corner or end block.

Fig. 8 shows a still further modified form ⁶⁰ of block structure; Fig. 9 the manner of superposing blocks of the type shown in Figs. 5 to 7 with a rod illustrated in Fig. 10 therebetween.

Fig. 11 shows the manner in which a wall ⁶⁵ of a building, such as a garage, is built up from the blocks and tie beams of my improved construction; Fig. 12 a horizontal section of the walls of the building shown in Fig. 11.

Fig. 13 is a partly sectional view of the tie ⁷⁰ rod or bolt used to join the blocks together and to the beams.

Fig. 14 illustrates further the manner of building up a partition from my improved blocks and beams; Fig. 15 a horizontal cross-⁷⁵ section of the partition illustrated in Fig. 14 with the manner in which the blocks in accordance with my improved construction may be positioned at points where two walls meet.

Fig. 16 illustrates the manner in which my invention may be utilized in the building up of a door.

Fig. 17 shows a modification of the type of tie rod or bolt illustrated in Fig. 13; Fig. 18 ⁸⁰ a further modification of the same.

Fig. 19 is a section along lines A—B of Fig. 16.

Referring more particularly to the drawings, the brick 20 is a rectangular block having parallel end surfaces from each end of which a shoulder 21 projects to form flanges which may be described as narrower blocks backing the rectangular shaped main portion 22. The flanges 21 are approximately one-⁸⁵ third the width of the main portion 22. When the two blocks illustrated in Figs. 1 and 2 are matched to form contiguous parts of a wall construction in accordance with my ⁹⁰ invention, the flanges 21 thereof engage the ¹⁰⁰ invention, the flanges 21 thereof engage the

respective end surfaces of the main portions 22, and embrace a beam 23 of steel or wood, depending upon the type of building or partition being built, spaced at regular intervals 5 along the line on which the wall is to be built in the manner clearly appearing from Fig. 4. The beam 23 is likewise about one-third the thickness of the brick 20 so that when the two flanges 21 of two adjacent bricks embrace 10 such beam, the surfaces of such adjacent bricks will present a smooth continuous plane. The bricks 20 are provided at the centers of each of the flanges 21 with apertures 24 co-operating with apertures of the same size and 15 drilled or bored into the beams 23 at intervals along its length corresponding to the horizontal center lines of the blocks 20. Through the apertures 24 and the corresponding apertures in the beams a tie rod or bolt 25 is 20 passed so that the bricks 20 and the beams 23 are joined by such tie rod or bolt as shown in Fig. 4. The blocks 20 are intended to fit closely against the beams 23 and the blocks are superimposed upon each other along the 25 vertical column to the full height of the wall, so that when the wall is complete there will be a smooth continuous surface over the whole space of the finished wall. As the bricks are constructed in standard sizes and beams 30 manufactured to fit such standard sizes, no difficulty will be encountered in properly locating the apertures in the flanges of the bricks or those along the length of the co-operating beams.

35 In Fig. 3 is illustrated a form of brick 26' which is designed to form a corner block, the construction of which permits the coming together of two walls built in accordance with my invention at right angles and without disrupting the manner or method of building up such wall as hereinbefore described. The corner block 26' comprises a main portion 27 and two flange portions 28 and 29 at right angles to each other and at 40 45 diagonal corners of the main portion 27 which come in contact with the wall structures meeting at the points where such corner block is to be located. The block 26 is also provided with apertures 24 in each of its flanges 28 and 29, which apertures are located so as to co-operate with the apertures in the beams which such corner blocks engage.

50 In order to obtain a closer union between superimposed blocks, I have provided an improved or preferable form of block illustrated in Figs. 5 to 7. Such blocks are provided with channels 30 and 31 at the centers of their longitudinal edges into which in the course of 55 60 65 constructing the wall may be placed metal rods 32 illustrated in Fig. 10, so as to make the joint between two superimposed layers of blocks air-tight. This construction is particularly important in the building up of walls, such as those of a bungalow, garage, etc., in open country where protection against

wind or rain getting inside the building through possible cracks at the jointure of such blocks is necessary. Fig. 9 illustrates more clearly the manner in which the rod 32 is placed between superimposed bricks.

70

In order to reduce the cost of construction and also to reduce the weight of my improved building block, I provide the preferable form thereof with interior spaces or holes 33 as shown in Fig. 8, of any form, running preferably the width of said blocks. These spaces, when the wall has been built up, co-operate with similar spaces running through superimposed blocks so that a convenient space within the wall structure is provided for electric wiring, gas or water piping, etc., the spaces 33 forming very desirable conduits for such wires or piping.

75

In Fig. 11 I have illustrated an entire side of a building built in accordance with my invention. In constructing a building such for instance as a garage, or a bungalow it is customary to make a foundation therefor of concrete, steel girders or similar frame structure. Horizontal supporting girders 34 to support the flooring of such a building are then placed upon such foundation 35, wooden beams 36 being preferably provided along the edges of the concrete or similar foundation. In accordance with my invention the beams 23 are then erected upon the line along which the wall is to be constructed at regular spaced intervals, depending upon the size of the bricks to be used in building the wall. The blocks 20 are then positioned as shown and as hereinbefore described in alternate order, so that their flanges embrace the beams 23 and the apertures 24 of the blocks and the beams co-operate to receive the tie rod or bolt 37. When the four walls of the building have thus been built up the roof 38 may be placed or built upon the structure in any well-known manner.

85

In Fig. 14 I have illustrated a partition wall which has been partially completed and which utilizes the end blocks 26 hereinbefore described. In Fig. 15 I have shown the manner in which such partition wall may be made to meet another wall built in accordance with my invention and at right angles thereto. The joining of two such walls may be accomplished either as is shown at the left of Fig. 15 by means of the corner block 26 being placed immediately adjacent the face of a full brick 20 of the meeting wall or as is shown at the right-hand end of Fig. 15, by the meeting of three end blocks in the manner shown. The form of meeting structure used will be dependent upon the space between two parallel walls in which space a partition is to be built.

90

In Figs. 16 and 19 I have illustrated the application of my improved construction to a door which has a frame 39 and vertical beams

130

or posts 40 similar to the beams 23 of my wall construction spaced along regular intervals within the frame. The bricks made in accordance with my invention may then be placed within the frame to cooperate with the said beams in like manner as the building up of a wall as hereinabove described.

Various forms of the tie rod or bolt 37 are illustrated in the drawings. In Fig. 13 is shown a tie rod made in two portions 41 and 42, the portion 42 having a threaded neck portion 43 which is adapted to be screwed into a threaded hole 44 of the part 41. The threaded neck portion 43 may be constructed independently of the portion 42 so that a turning of the head 45 of such neck portion will serve to lock the portion 42 into position against the face of the concrete block. As a smooth outer surface of a wall construction is desirable and in fact most necessary, the ends of the apertures 24 in flanges 21, which are adjacent the outer faces thereof, should be countersunk to receive the two heads of the bolt 37, so as to preserve the even smooth surface of the wall. In Figs. 17 and 18 I have shown two modified forms of tie rod or bolt which may be used in conjunction with a door which has been built up in accordance with my invention. These modified forms of bolt have heads which are not designed to be countersunk within the surface of the brick but on the contrary are designed to stand out from the surface thereof so as to present an appearance of ruggedness and strength.

It is obvious that while I have described the composition of my improved building blocks as concrete, cement, terra cotta, etc., such blocks may be made also of wood, when a temporary structure, such as a bazaar building, bungalow, or fence, is sought to be erected, or when it is desirable to have a building which may be put up or disassembled in very short time. It is likewise obvious that the blocks may be made of any size, considerable latitude even in the shape thereof being intended to be still within the scope and spirit of my invention.

It is to be noted that an important feature of my invention is the simplicity of the structure and the easy manner in which a building built in accordance therewith may be put up. The use of blocks cooperating with beams joined together by means of tie rods through apertures in said blocks and bricks in the manner hereinabove described presents a particularly facile manner of construction as the bricks are made somewhat self-adjusting, i. e. adjust themselves to their proper positions with respect to each other and the beam by the use of the tie bolt.

It is obvious that my invention is applicable to the construction of floors and roofs of buildings in which case the beams and blocks would be disposed horizontally. As I regard such a structure the equivalent of my

wall construction, being in fact, no more than a wall in a position other than the vertical, I have not described such flooring or roofing in the specification, or shown the same in the drawings.

I claim:

1. In a building wall construction, the combination, with upright supporting members suitably spaced along the line on which the wall is to be built, of molded blocks having a substantial thickness and flanged portions at their ends to embrace said upright supporting members when said blocks are positioned closely against the upright supporting members in a manner to present alternate faces thereof in one direction, said blocks and upright supporting members being provided with apertures in each of said flanges and along the length of the upright supporting member respectively, and tie-rods passing through said apertures securely fastening said blocks to said upright supporting members.

2. In a building wall construction, the combination, with upright supporting members suitably spaced along the line on which the wall is to be built, of molded blocks having a substantial thickness and flanged portions at their ends to embrace said upright supporting members when said blocks are positioned closely against the beams in a manner to present alternate faces thereof in one direction, and tie-rods securing said blocks to said upright supporting members along the length thereof.

3. In a building wall construction, the combination, with upright supporting members suitably spaced along the line on which the wall is to be built, of molded blocks having a substantial thickness and flanged portions at their ends to embrace said beams when said blocks are positioned with their end portions adjacent the upright supporting members so that the beams are entirely surrounded by said end and flanged portions and in a manner to present alternate faces thereof in one direction, said blocks and upright supporting members being provided with apertures in each of said flanges and along the length of the beam, respectively, and tie-rods passing through said apertures securely fastening said blocks to said upright supporting members.

4. Building wall construction as claimed in claim 2 in which the blocks are provided with holes running the width thereof superposed blocks having similar and cooperating apertures to form a conduit within the wall structure adapted to accommodate electric wires, gas piping or the like.

5. Building wall construction as claimed in claim 2 in which the tie-rods comprise bolts made in two portions secured together by a threaded neck projecting from one of said portions and adapted to be screwed into

a threaded seat provided therefor within the second portion.

6. Building wall construction as claimed in claim 2 in which the flanged portions of the molded block and the upright supporting member are each of a width equal to one-third the width of the whole block.

7. Building wall construction as claimed in claim 2 in which the flanged portions of 10 the molded blocks and the upright supporting members engaged thereby are of equal thickness.

8. Building wall construction as claimed in claim 2 in which the tie-rods comprise 15 bolts made in two portions in threaded engagement with each other, the heads of said bolts being countersunk into the molded blocks to present a smooth outer wall surface.

9. Building wall construction as claimed 20 in claim 2 in which the blocks are provided with channels along the centers of their longitudinal edges adapted to receive a rod, so as to make the joint between two superimposed blocks air-tight.

25 10. The combination, with vertically disposed upright supporting members, of a series of molded blocks having a substantial thickness and a back of narrower and longer blocks to form with said first mentioned 30 blocks flanged units embracing said upright supporting members when positioned against said beams in a manner to present alternate faces of said flanged units in one direction, and tie-rods passing through said flanged 35 portions and the upright supporting members engaged thereby to securely fasten said blocks to said upright supporting members.

11. A temporary structure capable of being disassembled without injury to the 40 units comprising the same, said structure consisting of a multiplicity of upright supporting members spaced apart, said upright members being rigid and self-supporting, a multiplicity of like blocks intermediate said 45 uprights, each block comprising a body portion and a flanged portion, the flange portion being of less width than the body portion, the flanges of said flanged portion being matched by the overlapping of the flanges of adjacent 50 blocks, the flanges, by reason of their relative thinness with respect to the body portion, providing a space between matched flanges for said upright.

ALFRED GIULIANI.
